UNITED STATES PATENT OFFICE

HANS MARBURG, OF BERLIN-HALENSEE, GERMANY, ASSIGNOR TO TELEPHON-APPARATE FABRIK E. ZWIETUSCH & CO., G. M. B. H., OF BERLIN-CHARLOTTENBURG, GERMANY, A CORPORATION

CARTRIDGE SEPARATING DEVICE FOR PNEUMATIC TUBE PLANTS

Application filed November 19, 1929, Serial No. 408,297, and in Germany November 24, 1928.

This invention relates to a cartridge separating device for pneumatic tube plants and is intended for automatically regulating the travelling distance between cartridges following closely the one behind the other.

In the known cartridge separating devices of this type the arrested cartridges cannot be locked for any desired length of time, as the release of the locking is effected each time 5 mechanically or pneumatically shortly after the passing of a cartridge. Consequently the cartridges are only separated the one from the other by a comparatively short distance whereby, owing to the unequal loading 10 or wear of the running cases, it is possible that the cartridges catch up or pass over the same switch although a different switching was intended for the second, following cartridge.

Further in the known retaining devices each cartridge has to operate levers for locking the cartridge directly following which levers, owing to their mechanical cooperation 20 with the actual locking elements, exert a checking effect on the running of the cartridges so that, for example upon the restarting of the blower, the cartridges, situated shortly before this separating device, have not yet the necessary speed, for actuating 25 an according lever mechanism, and consequently a jamming of these cartridges may easily occur.

These defects connected with the known retaining devices working with mechanical 30 or pneumatic control are absolutely overcome by the present invention in the most simple manner in that an electromagnetically operating locking device is used for regulating the travelling distance between a number of 35 cartridges arriving at the same time. Such an arrangement offers very considerable advantages over the known arrangements in that the force required for stopping the following cartridge is not applied through a 40 lever mechanism by the cartridge itself, but

the travelling cartridge only actuates an easily movable contact arm, which transmits to an electromagnet the force necessary for the locking of the cartridge.

Two embodiments of the invention are 50 illustrated by way of example in the accompanying drawings in which:—

Fig. 1 shows a section through the housing of the separating device seen from the side, the device being in position of rest.

Fig. 2 is a vertical section seen from the front of the housing of the separating device, showing the lateral arrangement of the magnet and also of the contacts controlled by the contact lever.

Fig. 3 shows the separating device in side elevation and indicates the current flow necessary for actuating the device.

Fig. 4 shows a modified form of construction of the separating device in longitudinal section, a contact segment at the same time constructed as locking element, being in the position of rest.

Fig. 5 is a similar view to Fig. 4, showing the locking position of the contact segment.

Fig. 6 is a similar view to Figs. 4 and 5, showing the release or further swinging out of the contact segment, so that the first cartridge is released and at the same time the next following cartridge is locked.

A housing 1 arranged at the side of the tube 2 accommodates a control element 3 mounted on an axle 6 and controlling, by means of a projection 7 and a spring 5 a locking fork 4 loosely mounted on the axle 6 and adapted 80 to project through a slot 8 of the tube 2. On the outer end of the journalled axle 6, outside the housing 1, a lever arm 13 is fixed adapted to cooperate with an electro-magnet 12. This lever 13 controls by means of a laterally projecting arm 13' a retaining contact 6, and is returned into its inoperative position up to a stop 17 by a spring 16. In the lower part of the housing 1 a contact lever 10 is mounted on a rotatable shaft 11, said lever 90

projecting through a guide slot 9, and it is held in its operative position by a spring 15. A cam 14 which controls contacts *a* and *b* is mounted on the rotatable shaft 11 on the outer side of the housing 1.

The above described cartridge separating device (Figs. 1 to 3) is intended to allow the first of a number of cartridges arriving to travel on unimpeded and to retain electro-magnetically the following cartridges until these are released singly at intervals for continuing their travel. According to the invention this is effected in that the cartridge travelling in the direction of the arrow 10 magnetically depresses the contact lever 10 so that it oscillates out of the path. At the same time the cam 14 is rotated, and the contacts *a*, *b* are closed so that current is sent to the magnet 12. The control element 3 is thereby oscillated through the lever 13 and the shaft 6 and with the same the locking fork 4, resiliently connected with the control element 3, is oscillated so that it projects through the slot 8 into the tube and arrests the following cartridges. The contact lever 10 is returned into its inoperative position by the spring 15, the contact at *a*, *b* being broken at the same time, whereas the electro-magnet 12 remains excited over the contact *c* until the first cartridge cuts the current off from the magnet 12 after a certain predetermined time by actuating a second contact *f* in the tube, or any other suitable controlling means, whereby the locking of the next following cartridge 35 is removed. This cartridge then again controls the contact arm 10 and the locking operation above described repeats itself with the following cartridges. It is evident that also in the locking device above described all cartridges arriving singly at certain time intervals can pass directly through the separating device.

The cartridge separating device shown diagrammatically in Figs. 4 to 6 is intended to first lock each cartridge and then to release the same singly after a certain predetermined time. With this object in view a housing 18 is mounted on the tube 19. An oscillating lever 20 mounted on a rotatable shaft 21 is located in said housing said lever being resiliently connected by means of a spring 22 and projection 22' with a locking fork 21, in similar manner as the lever 3 in Figs. 1 and 2. Below the oscillatable lever 20 a contact segment 23 is arranged on a rotatable shaft 23'. This segment has a projection projecting into the tube 19 and adapted to be pushed back into its inoperative stop position under the action of a spring, not shown. The turning of the shaft 21 is effected in a similar manner as shaft 6 (see Figs. 1 to 3) by means of a magnet, whereas a contact disc, not shown, is keyed on the rotatable shaft 23' of the contact segment 23 on the outer side 65 of the housing 18.

The above described separating device operates in such a manner that the cartridge 25 arriving in the direction of the arrow first turns the contact segment 23 against the stop 20' of the lever 20 which holds the segment in this position. Owing to the turning of the contact segment 23 into the stop position (Fig. 5) contacts are operated by a contact disc, not shown, which contacts are necessary for different switching operations. If the tube is free, an electromagnet connected with the shaft 21' is excited and the next following cartridge 24 stopped. At the same time the stop 20' of the lever 20 slides off the contact segment 23, which is then moved out of the path by the departing cartridge 25, this turning movement being again utilized for controlling any other contacts. After the passing of the cartridge the segment 23 returns under spring action into its inoperative stop position thereby cutting the current off from the magnet. The cartridge hitherto held by the locking fork 21 now slides onto the contact segment 23 into the waiting position and the locking or releasing above described is repeated in the same manner for the following cartridges.

A contact disc is also fixed on the shaft 23' of the contact segment 23, as shown in Figs. 2 and 3, which disc controls suitably arranged contacts during its rotation. Thus for example during the first movement of the contact segment 23 up to the stop 20' the waiting condition of a cartridge is indicated by a signal lamp. When the first cartridge is released or the next following cartridge locked, another controlling operation, for example the indicating of the dispatch of the cartridge by means of a light signal or the operating of a switch can be effected by the further movement of the contact segment 23 in the direction of travel.

I claim:

1. An electrically controlled device for pneumatic tube plants for regulating the distance between the cartridges at any desired point of the tube, comprising in combination with the cartridges, an absolutely automatically operating locking device, adapted to lock said cartridges, contacts, and electro-magnets controlling said locking device.

2. An electrically controlled device for pneumatic tube plants as specified in claim 1, comprising in combination with the cartridges, the locking device and the contacts and magnets, a lever of said locking device adapted to allow the passage of the first of a plurality of arriving cartridges, to arrest the following cartridges through the intermediary of said contacts and said magnets, and to release these arrested cartridges singly at predetermined intervals.

3. An electrically controlled device for pneumatic tube plants as specified in claim 1, comprising in combination with the car-

tridges and the contacts, a locking element in form of a contact segment adapted to control said contacts, to arrest each cartridge as it arrives and to release same for travelling on, at the same time locking the next following cartridge.

4. An electrically controlled device for pneumatic tube plants as specified in claim 1, comprising in combination with the pneumatic tube, the locking device and the contacts and magnets controlling said locking device, a housing communicating with said tube carrying on its outer side said magnets and contacts.

15 In testimony whereof I affix my signature.
HANS MARBURG.
